UNITED STATES PATENT OFFICE

ARVID S. JOHNSON, OF AUBURN, AND HERBERT W. NEUNHERZ, OF GARDNER, MASSACHUSETTS, ASSIGNORS TO GEM CRIB & CRADLE COMPANY, OF GARDNER, MASSACHUSETTS, A CORPORATION OF MASSACHUSETTS

BUFFING MACHINE

Application filed August 6, 1931. Serial No. 555,554.

This invention relates to a machine for rapidly buffing rods of considerable length. The principal objects of the invention are to provide a machine in which the rods can be inserted almost instantaneously and from which they can be taken out after buffing just as quickly; to provide for giving a continuous feed to a carriage on which the work is located; to provide means whereby at the start 10 the rod will be polished as much as it will elsewhere; to provide an improved form of holder for the rods; to provide a simple construction in which the rod can be moved back away from the buffing wheel for the exchange 15 of a completed rod for a new one and to provide convenient means for rotating the rod when its surface is being polished.

Other objects and advantages of the invention will appear hereinafter.

Reference is to be had to the accompanying drawings, in which

Fig. 1 is a plan of a machine constructed in accordance with this invention showing the beginning of the operation;

Fig. 2 is a sectional view on the line 2—2 of Fig. 1;

Fig. 3 is a sectional view on the line 3—3 of Fig. 1 showing the end support for the rod to be buffed;

Fig. 4 is a sectional view on the line 4—4 of Fig. 1, showing one of the rests in which the rods are to be put when they are taken out of the machine;

Fig. 5 is a sectional view on the line 5—5 of Fig. 1 showing the connection between the screw and the rotating means for the rod;

Fig. 6 is an enlarged plan of the means for holding and rotating one end of the rod;

Fig. 7 is an end view looking in the direction of the arrow 7 in Fig. 6, showing the holding means;

Fig. 8 is a view of a bed post rod on which the machine is adapted to operate, and

Fig. 9 is a view of a modification showing 45 a means for holding the end of the rod when a straight metal or wooden rod is to be buffed or polished on this machine.

The machine shown is designated for polishing or buffing rather long cylindrical bed 50 post rods, particularly of the type shown in

Fig. 8. This rod 10 is provided with an end 11 bent at right angles thereto and most of the description will refer to the operation of the machine on a rod of that general shape. The machine is capable of use on cylindrical rods of many other types and can be used to smooth wooden rods, using a sand wheel.

Heretofore the polishing operation has been done practically by hand, the operator handling the rod and one of the objects of this invention is to provide means whereby the rod is simply inserted in the machine in a very quick manner and the rest of the operation is performed automatically except the removal of the rod.

The machine is shown operated by a motor 12, which, through any means of transmission, rotates a feed screw 13. This feed screw 13 is mounted on stationary bearings on the frame 14 of the machine. This frame is provided with a pivot shaft 15 or studs for pivotally holding a frame 16. Normally this frame 16 rests on an adjustable stop 9. From the frame 16, extending down to a point near the floor, is means for supporting a pedal 17. This pedal can be forced down by the foot, as will be seen later, to draw back the work from the buffing wheel 18, or a wheel carried with sand paper, against the opposition of a spring 39. This wheel is mounted on a shaft 19, carried by the frame, and rotated either by the motor 12 or in any desired way.

The frame 16 is provided with a support and guide 20 in which is mounted a slide 21, ways or gib 22 being provided to hold the slide to move longitudinally but not otherwise.

This slide carries at one end a bracket 23 on which is a circular support 24 for the extreme end of the rod and, of course, this support moves with the slide. Also mounted

on the frame 16 in stationary position is a backing up bracket 25 having a rest 26, which is not circular but provides a shelf-like support against which the rod is held. This back

up rest is located in registration with the buffing or polishing wheel 18 and does not move except as the frame 16 is tilted back as before stated.

On the slide 21 is mounted a frame 27 on which is a shaft 28, mounted to be free to

rotate in the frame 27. To this shaft is keyed a disc or wheel 29 capable of moving longitudinally on the shaft 28 but slidingly keyed to it so as to be adapted to rotate it.

5 A spring 30 bearing on the frame 27 normally holds this disc in the position shown in Fig. 6. Connected with the slide 21 or the frame 27 is a cable 31 passing over pulleys 32 and having a weight 33 thereon, which of course, hangs downwardly and normally pulls the slide back and holds the disc 29 in frictional engagement with the screw threads. The disc 29 projects in between the screw threads on the screw 13 and of course, it is forced to move longitudinally as the screw is rotated. Furthermore, it is forced to rotate by friction with the threads of the screw.

10 The end of the shaft 28 is provided with a holding means for the end 11 of the wire 10. This comprises a longitudinal slot 34 and a radial slot 36 through which the end 11 of the wire can extend. It also includes a pair of opposite round ended pins 35 pressed inwardly by a spring 46 to enter the slot 34.

15 It will be seen that when the shaft 28 is positioned, as shown in Figs. 1, 6 and 7, with this slot 34 at the top and the slot 36 vertical, the end of the rod can be forced in past the round ended pins 35 clear to the center of this shaft where it comes up against the semicylindrical end of the slot 34. The pins 35 prevent its being dislodged by any ordinary forces.

20 In this way it will be seen that the rods are centered at both ends and backed up at the end of the buffing wheel. Now, with the parts as shown in Fig. 1, the motor 12 is started and the buffing wheel also is rotated at full speed. The rotation of the screw rotates the disc 29 in this position until the spring 30 is pressed sufficiently to cause further rotation of the screw to move the whole slide 21 along with the disc. During this period, the rod 10 will turn a few turns and receive an even buffing action at its advance end. After that, the slide 21 will move along until the disc 29 is nearly at the end of the screw and the entire straight surface of the rod is buffed except for the two extreme ends which are in the supports.

25 Now the operator presses on the pedal 17 and he not only moves the rod, which has been buffed, away from the buffing wheel but he also moves the disc 29, carried on the frame 16, away from the screw. The screw and buffing wheel therefore can be allowed to continue to rotate and they do not have to be stopped between operations. The operator now pulls the right hand end of the rod out of the holder between the pins 35, removes the rod, and deposits it in a pair of supports 37, two of them being enough to support a bundle of these rods.

30 From this it will be seen that the machine is not only simple but the rods can be applied,

removed, put in a place for temporary storage, a new rod applied and the new rod put into engagement with the buffing wheel while the slide 21 is moved back by the weight 33 to the position shown in Fig. 1, ready for 70 a new operation. This greatly simplifies all the operations and reduces the cost thereof very materially.

In Fig. 9 a simple modification is shown in which on the shaft 28 is mounted a chuck 39 75 for holding a straight rod 40, a screw 41 being applied to secure it in position. Therefore this machine is capable of operating on the rods illustrated in Fig. 8 and also on straight rods almost with equal facility.

80 Although we have illustrated and described only two forms of the invention we are aware of the fact that other modifications can be made therein by any person skilled in the art without departing from the spirit 85 of the invention as expressed in the claims. Therefore we do not wish to be limited in this respect but what we do claim is:—

1. In a machine for buffing rods or the like, the combination of a slide having a support 90 for one end of the rod carried thereon, a rotatable support carried by the slide for the other end of the rod, a disc connected with the rotatable support to rotate it, and a rotatable screw, said disc projecting between the screw threads, whereby it will be rotated and moved longitudinally by the rotation of the screw and will carry the rod with it.

2. In a machine for buffing rods and the like, the combination of a slide having a support 100 for the rod carried thereon, a rotatable support carried by the slide for the other end of the rod, a disc connected with the rotatable support to rotate it, a screw, means for rotating the screw, said disc being located to project between the screw threads, whereby it will be rotated and moved longitudinally by that rotation, and means for mounting the disc on the slide for the purpose of moving the slide along in a line parallel with the rod and the axis of the screw.

105 3. In a machine for buffing rods and the like, the combination with a rotary buffing wheel, of a slide movable in a direction parallel to the axis of the buffing wheel, said slide carrying means for supporting the end of the rod in position to be buffed by the wheel, a rotary shaft carried by the slide having means for supporting the opposite end of the rod, a disc slidably keyed to the shaft, and a rotatable screw between the threads of which the disc projects, whereby the rotation of the screw will rotate the disc and rod and cause the disc, together with the slide on which it is mounted, to move longitudinally, the rod being supported in a position to engage the wheel.

110 4. In a buffing machine, the combination of a slide for carrying the work, said slide having a rotatable shaft thereon constituting

a support for one end of the work, a frame on the slide having bearings for the shaft, a disc slidably keyed to the shaft to rotate it, a spring between one side of the frame and the disc and a screw engaging the disc for rotating the disc and moving the slide.

5. In a machine for buffing rods and the like, the combination with a rotary buffing wheel, of a slide, means for guiding the slide to move longitudinally of the machine, two supports carried by the slide for the opposite ends of the rod, one being stationary and the other rotatable and being in position to hold the rod against the buffing wheel, a shaft carried by the slide on which the rotatable support is mounted, a disc slidable on said shaft and slidably keyed thereto, a spring normally forcing the disc back on the shaft, a rotatable screw between the threads of which the disc projects, whereby, when the screw starts to rotate, the rod will be given several turns before the slide will start to move, due to the action of the screw on the disc, thereby polishing the end of the rod more than the rest of it.

6. In a buffing machine, the combination with a rotary buffing wheel, of a frame having longitudinal ways, a slide mounted to move in said ways, a counterweight for normally moving the slide backwardly, a shaft rotatably mounted on the slide, a disc keyed to the shaft, a screw into the threads of which the disc projects and against which the disc is held by the counterweight, whereby the rotation of the screw will rotate the disc and move the slide in its ways.

7. In a buffing machine, the combination with a rotary buffing wheel, of a screw mounted on an axis parallel with the axis of the buffing wheel, a stationary frame on which the buffing wheel and screw are mounted, said frame having pivots or bearings, an oscillating frame mounted on said pivots and having longitudinal ways, a slide movable in said ways, a disc carried by the slide and cooperating with the screw for moving the slide, means on the slide for carrying the work along the surface of the buffing wheel, said pivoted frame being adapted to swing back on its pivot to bring the disc out of contact with the screw for removal and replacement of the work.

8. In a buffing machine, the combination with a rotary buffing wheel, of a screw mounted on an axis parallel with the axis of the buffing wheel, means for rotating the screw, a stationary frame on which the buffing wheel and screw are mounted, said frame having pivots or bearings, an oscillating frame mounted on said pivots and having longitudinal ways, a slide movable in said ways, means always acting on the slide to move it in one direction, a disc carried by the slide and cooperating with the screw for moving the slide in the opposite direction, means on the slide for

carrying the work along the surface of the buffing wheel, said pivoted frame being adapted to swing back on its pivot to bring the work back from the buffing wheel and the disc out of contact with the screw for removal and replacement of the work.

9. In a machine of the character described, the combination of a rotary buffing wheel and a rotary screw mounted on parallel axes, a stationary frame on which they are supported, an oscillatable frame pivoted on the first named frame on a longitudinal axis, means carried by the oscillatable frame for pressing the work against the buffing wheel, means carried by the oscillating frame for 80 rotating the work from the screw and moving the work longitudinally from the rotation of the screw, and a treadle connected with said oscillating frame for swinging the frame back to a position in which the work 85 will be out of contact with said buffing wheel.

In testimony whereof we have hereunto affixed our signatures.

ARVID S. JOHNSON.
